Patented Jan. 10, 1961

189,586

TUMBLER

George S. Nalle, Jr., 108 W. 2nd St., Austin, Tex.

Filed May 31, 1960, Ser. No. 60,790

Term of patent 14 years

(Cl. D36—8)

Fig. 1 is a side elevation of the tumbler embodying my invention;

Fig. 2 is a top plan view thereof;

Fig. 3 is a bottom plan view thereof; and

Fig. 4 is a fragmentary section through the walls of the tumbler, shown on an enlarged scale.

The design is characterized by the moire-type appearance depicted in Fig. 1, which is created by the angular relationship between the flutings on the outer wall, which are translucent, and the dark stripes or lines on a sheet or liner placed inside the outer wall, this appearance changing with the angle of view of the observer.

I claim:

The ornamental design for a tumbler, as shown and described.
